United States Patent Office

Des. 191,360
Patented Sept. 19, 1961

191,360

READING STAND

Stanton B. Bolcom, Minneapolis, Minn.

Filed Sept. 12, 1960, Ser. No. 62,122

Term of patent 14 years

(Cl. D33—10)

Fig 2

Fig 3

FIGURE 1 is a perspective view of a reading stand, showing my design;

FIGURE 2 is a side elevational view on a reduced scale; and

FIGURE 3 is a sectional view on a reduced scale and taken along the lines 3—3 of FIGURE 1.

I claim:

The ornamental design for a reading stand, substantially as shown.
